SELF-ADJUSTING MAN'S GARTER

Maurice M. Halliss, Kew Gardens, N. Y.

Application February 14, 1945, Serial No. 577,775

3 Claims. (Cl. 2-316)

1

This invention relates to new and useful improvements in a self-adjusting man's garter.

More specifically, the invention proposes an improved man's garter which is characterized by a flat hook-like ring clip having a flat base connecting into a short arcuate neck continuing into a flat top hook portion. A garter strap is attached to said flat base for extending around one's leg and then through said clip and then down for connection with the top of a piece of hose by a detachable and adjustable gripping device.

The invention contemplates providing said short arcuate neck with serrations or other gripping elements for gripping said garter strap to prevent slipping and sliding.

Still further the invention proposes a modified form embodying the essential characteristics of the preferred form, including an arrangement for supporting and holding the garter strap from crumpling at the area passing around said short arcuate neck.

Still further the invention proposes the construction of a self-adjusting man's garter which is simple, efficient and desirable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is an illustration of a leg provided with a self-adjusting man's garter constructed in accordance with this invention.

Fig. 2 is an enlarged fragmentary elevational view of the self-adjusting man's garter, illustrated per se.

Fig. 3 is a fragmentary vertical sectional view taken on the line 3-3 of Fig. 2.

Fig. 4 is a view similar to Fig. 3 showing some of the members separated.

Fig. 5 is a fragmentary transverse sectional view taken on the line 5-5 of Fig. 3.

Fig. 6 is an enlarged bottom view of the ring clip used in the garter.

Fig. 7 is a view similar to Fig. 5 but illustrating a further modification of the ring clip.

Fig. 8 is a fragmentary elevational view of the bottom portion of another strap to be used in the man's garter.

Fig. 9 is a vertical sectional view taken on the line 9-9 of Fig. 8.

2

Fig. 10 is a fragmentary illustration similar to Fig. 1 but disclosing a modified construction of the man's garter.

Fig. 11 is a fragmentary enlarged horizontal sectional view taken on the line 11-11 of Fig. 10.

The self-adjusting man's garter, in accordance with that form of the invention disclosed in Figs. 1 to 6 inclusive, includes a flat hook-like ring clip, 10 having a flat base, 11 continuing into a short arcuate neck 12 which continues into a flat top hook portion 13. A garter strap 14 is attached to said flat base 11 and is intended to extend around one's leg and then through said clip 10 and then down for connection with the top of a piece of hose by a detachable and adjustable gripping device. The flat base 11 is formed with an opening 16 through which the end of the strap 14 is engaged and turned down. The turned down portion of said strap 14 is secured in position by a line of stitches 17. The garter strap 14 may be in the nature of a ribbon, a strap, an elastic strap, or any other suitable garter strap.

The short arcuate neck 12 is formed with several serrations 20, or gripping elements, or portions. These serrations 20 extend radially along the flat base 11 and are capable of engaging the strap 14 for holding the strap from sliding. The free end of the strap 14 is provided with a detachable and adjustable gripping device by which the strap 14 may be connected with the top of a piece of hose. This detachable and adjustable gripping device comprises a back plate 21 and a front plate 22. The back plate 21 is formed with a plurality of spaced openings 21^c and 21^d, and the front plate 22 is formed with an opening 23. The strap 14 is laced through openings 21^c and 21^d to facilitate its gripping and adjustment in plate 21, and through opening 23 in plate 22 and through the upper opening 21^c in plate 21 to allow the strap 14 to move freely for adjustment. The lower edge of opening 23 in the front portion 22 and the upper edge of the opening 21^d in the rear portion 21 are formed with gripping teeth for firmly holding the strap 14. The back plate is provided with a hook-like projection 24 which engages a complementary bayonet opening 25 in the front plate 22, by which the detachable and adjustable gripping device may be connected with the top edge portion of a piece of hose. The back plate 21 is also provided with inward projections 21^a, spaced at 21^b to permit the strap 14 to be inserted when the garter is in gripping position, and to be removed when it is desired to disengage the hose. When the strap

14 is removed through the spacing 21^b, the plates 21 and 22 may be separated as shown in Fig. 4. In Fig. 1 the garter is shown in position on a leg 26. It should be noted that the strap 14 extends from the flat base 11 around the leg, and then through the ring clip 10, and then down to the leg, and then down to the hose 27. In Fig. 7 short ribs 20' are provided in the arcuate neck 12'. Raised surfaces 20^a extend inwardly and in interlocking relation, from the base 11 and the hook portion 13 to grip the strap 14.

In Figs. 8 and 9 another embodiment of the same invention is disclosed. In this embodiment the strap 14 is provided with an adjustment buckle 30 by which portions of it may be let out or pulled into control the length of the strap. The strap 14 is also provided with a gripping device, comprising a back plate 31 and a front plate 32. The back plate 31 has a hook element 33 which is engageable through a bayonet slot 35 formed in the front plate 32.

In Figs. 10 and 11 still another form of the invention has been disclosed which is very similar to the prior form distinguishing merely in the fact that the flat hook-like ring clip 38 as a flat base 39 which continues into a short arcuate neck 40 which in turn continues into a flat top hook portion 41. The outer edge of this flat top hook 41 is formed with an outwardly flared flange portion 42 at the base of which there is a groove 43. This groove 43 extends arcuately along the arcuate edge of the flat top hook portion 41. The outer edges 44 of the garter strap 14 are enlarged, or thickened, or formed with a flexible bead. This may be done by rolling the edge portions of the strap 14. The beaded, or rolled edges 44 are sewed or cemented to maintain its thickened form.

One of the other of the beaded or rolled edges 44 is capable of being snipped inwardly past the flared flange portion 42 of the top hook portion 41 so as to assume a position along the length of the groove 43. The flexible beads 44 supports the outer edge of the strap 14 preventing it from becoming crumpled within the hook portion 41 of the ring clip 38. The strap 14 is capable of being slipped forwards or backwards through the ring clip 38. It may also be removed from the groove 43 merely by pulling it out. The flat top hook portion 41 then flexes outwards, while the strap comes out.

In other respects this form of the invention is identical to the prior form and like parts may be recognized by like reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A self-adjusting man's garter, comprising a detachable and adjustable hose gripping device, a flat hook-like ring clip having a flat base continuing into a short arcuate neck continuing into a flat top hook portion, said clip being flanged to form a groove, a garter strap attached to said flat base for extending about one's leg and then through said clip and then down for connection with the top of a piece of hose by said detachable and adjustable gripping device, and an outer edge of said strap extending through said clip and having a flexible bead engaging in said groove.
2. A self-adjusting man's garter, comprising a detachable and adjustable hose gripping device, a flat hook-like ring clip having a flat base continuing into a short arcuate neck continuing into a flat top hook portion, a garter strap attached to said flat base for extending about one's leg and then through said clip and then down for connection with the top of a piece of hose by said detachable and adjustable gripping device, said clip being flanged to provide a groove and an outer edge of said strap extending through said clip and having a flexible bead engaging in said groove formed arcuately along the edge portion of said hook portion by said flange, said flexible bead comprising a thickened portion upon the edge of said garter strap.

3. A self-adjusting man's garter, comprising a detachable and adjustable hose gripping device, a flat hook-like ring clip having a flat base continuing into a short arcuate neck continuing into a flat top hook portion, a garter strap attached to said flat top base for extending about one's leg and then through said clip and then down for connection with the top of a piece of hose by said detachable and adjustable gripping device, said clip being flanged to provide a groove and an outer edge of said strap extending through said clip and having a flexible bead engaging through said groove formed arcuately along the edge portion of said hook portion, and the edge portion of said hook portion being arcuate and flanged outwards.

MAURICE M. HALLISS.
